UNITED STATES PATENT OFFICE.

MICHAEL J. NOLAN, OF CHICAGO, ILLINOIS.

TOILET-BOX.

1,269,207.

Specification of Letters Patent. Patented June 11, 1918.

Application filed November 6, 1916. Serial No. 129,732.

To all whom it may concern:

Be it known that I, MICHAEL J. NOLAN, a citizen of the United States, residing at Chicago, in the county of Cook and State 5 of Illinois, have invented certain Improvements in Toilet-Boxes; and I do hereby declare that the following is a full, clear, and exact description thereof, reference being had to the accompanying drawings, and to 10 the characters of reference marked thereon, which form a part of this specification.

This invention relates to a novel toilet article in the nature of a combined powder and rouge box for ladies' use, embracing in 15 a unitary structure, a separate compartment for each a face powder and a rouge block and a powder puff for each block, the parts being arranged to provide a compact multi-container provided with separate end closures, whereby the puffs may be separately 20 used at will.

The invention consists in the combination and arrangement of the parts shown in the drawings and described in the specification, 25 and the invention is pointed out in the appended claim.

In the drawings:

Figure 1 is a perspective view of a toilet box embodying my invention.

30 Fig. 2 is an axial section thereof.

The box shown in Figs. 1 and 2 comprises two cylindric or other suitably shaped shells 10, 11 axially aligned and arranged end to end, a transverse partition or diaphragm 35 12 between the ends of the shells, a band 13 surrounding the shells and overlapping said shells a distance above and below said partition and top and bottom covers 14, 15, fitted to the upper and lower open ends of the shells 10 and 11 respectively. The diameter of the diaphragm 12 is equal to the external diameter of the shells, so that the periphery of the partition is coincident with the circumference of the shells. Said shells abut 40 squarely against the upper and lower faces of said partition and may be pasted thereto.

The band or ring 13 surrounds the connected shells at the union between the same and the partition or diaphragm and is 50 glued, cemented or otherwise secured to said shells. By reason of the overlapping of said ring a distance beyond the proximate marginal portions of said shells, and by reason of the bridging of said ring across the edge 55 of said partition, said ring serves, not only to join the shell members together, but also

to fix the said partition reliably to the members of the two part shell, and further to produce a very strong and rugged box.

The top and bottom covers 14 and 15 are 60 provided with flanges 17 and 18, respectively, which telescope over the opposite ends of said shells to close the upper and lower compartments between the central partition 12 and said end covers. Preferably 65 said cover flanges are made of a length to abut at their free or inner edges against the opposite edges of the band or ring 13 and said cover flanges will preferably be made of the same thickness as said ring 13 so that 70 the cover rims or flanges fit flush against said band or ring, and the complete box is cylindrically continuous or unbroken from end to end. Preferably the said band or ring 13 is made of some width so as to afford, 75 in addition to its function of binding together the upper and lower shells of the box and fixing the partition or diaphragm relatively to said shells, a gripping or holding member which may be engaged by one 80 hand of the user to hold the box when one of the covers is to be removed and thereby avoid dislodging the other cover.

The ring 13, in addition to its function of uniting the upper and lower shells and the 85 intermediate partition of the box and affording a grip by which the box, as a whole, may be held while a cover is removed therefrom, constitutes also a suitably dimensioned 90 annular area to receive a label.

The single diaphragm or partition 12 constitutes a backing and support at one side for a block 25 of face powder and at its other side a support and backing for a block 26 of rouge; the powder and rouge being 95 preferably mixed with a binder by which the shape and dimensions of the material are maintained. The chambers or compartments between the block supporting and backing partition 12 and the end covers are 100 preferably made sufficiently deep to receive the usual powder puffs 27, 28.

In some instances the diaphragm 12 of Fig. 2 may be an integral part of one of the shell members 10 or 11.

100 I claim as my invention:

A toilet box of the character described, comprising shells of equal diameters arranged in axial alinement with each other and disposed end to end, a disk like partition interposed between the adjacent inner ends of said shells, the peripheral edge of

the partition being flush with the outer surfaces of the shells and the inner ends of the latter abutting said partition, a relatively wide band concentrically of the shells medially thereof and overlapping the same a distance above and below the partition, and covers having rims removably telescoped over the outer ends of said shells with the outer faces of said rims and band flush with each other.

In witness whereof I claim the foregoing as my invention, I hereunto append my signature in the presence of two witnesses at Chicago, Illinois, this 3rd day of November, 1916.

MICHAEL J. NOLAN.
